(57) **CLAIM**

What is claimed is the ornamental design for a mark making roller, as shown and described.

DESCRIPTION

FIG. 1 is an upper perspective view showing the mark making roller of Applicants' invention.

FIG. 2 is a lower perspective view of the mark making roller of FIG. 1.

FIG. 3 is a front elevation of the mark making roller of FIG. 1, with the rear elevation view being a mirror image thereof; and,

FIG. 4 is top plan view of the mark making roller of FIG. 1, with the left, right, and bottom plan view being mirror images thereof.

The broken lines show portions of a mark making roller which form no part of the claimed design.

The area within the dash-dot brackets are meant to convey an unspecified length, and forms no part of the claimed design.
